UNITED STATES PATENT OFFICE.

STACY B. HASELTINE, OF CHICAGO, ILLINOIS, ASSIGNOR, BY MESNE ASSIGNMENTS,
TO W. H. MINER, INC., A CORPORATION OF DELAWARE.

DOOR OPERATING AND LOCKING DEVICE.

Application filed January 7, 1924. Serial No. 684,691.

To all whom it may concern:

Be it known that I, STACY B. HASELTINE, a citizen of the United States, residing at Chicago, in the county of Cook and State of Illinois, have invented a certain new and useful Improvement in Door Operating and Locking Devices, of which the following is a full, clear, concise, and exact description, reference being had to the accompanying drawings, forming a part of this specification.

This invention relates to improvements in door operating and locking devices.

The object of this invention is to provide a simple and relatively inexpensive device which can be applied to a door of the sliding type and which will have effective means for drawing the door to tightly closed position, which will be of service in starting the opening operation, and by which the door may be securely locked when closed.

In the drawing forming a part of this specification, Figure 1 is a side elevation of a portion of a box car, showing a portion of the side door thereof with my improvements in connection therewith. Fig. 2 is a horizontal, sectional view corresponding substantially to the line 2-2 of Fig. 1. Fig. 3 is a vertical, sectional view corresponding substantially to the line 3-3 of Fig. 1. And Fig. 4 is a detailed, side elevational view of a latch member used in connection with my improved device.

In said drawing, 10 indicates the sliding side door of a railway box car, which may be either of the top or bottom hung type. One of the door posts is indicated at 11 in Fig. 2, the latter being cut away as shown at its outer side to provide a door stop 12 against which the forward edge 13 of the door is adapted to bear when the door is in fully closed position.

The improved door operating and locking device, as shown, comprises, broadly, a stop bracket A; a pivoted locking plate B; a sliding bar or link C; a latch member D; a guide bracket E; a pair of supporting brackets F-F; and an operating lever G.

The pair of supporting brackets F-F are of like construction, each including a base plate 14 suitably bolted or riveted to the door as indicated at 15. Formed integral with each plate 14 is an outwardly projecting, horizontally disposed flange 16 of triangular outline, having a bearing 17 formed

at its outer end, said bearing being in the form of a boss provided with a cylindrical bore. The supporting brackets F are arranged with the sides thereof carrying the flanges 16 adjacent, the flanges being disposed in spaced parallel relation and the bores of the bearing 17 in alinement.

The lever G comprises a bifurcated head section 18 and an operating handle 19, the latter being pivotally connected to the section 18 by means of a pin 20 extending through the end of the same and a tongue 21 formed integral with the section 18, the pivoted end of the handle being preferably provided with a substantially circular enlargement 22 slotted to receive the tongue 21 and provided with alined perforations adapted to receive a pivot pin 20. The free ends of the arms of the forked head section 18 are connected by a pin 23. The head 18 is disposed between the flanges 16 of the brackets F and, at a point intermediate the ends thereof, each arm of the fork is provided with a trunnion 24 journaled in the bearing 17 of the corresponding bracket F. The head is thus pivotally mounted between the brackets F-F to swing in a horizontal plane. Upon reference to Figures 1 and 2, it will be seen that the handle 19 is pivoted to the head 18 so as to swing at right angles thereto, thereby permitting the handle to be raised by the operator so as to assume a convenient position for oscillating the head 18, and also allowing the handle to drop under the influence of gravity to the dotted line position shown in Figure 1, when released by the operator. The enlargement 22 is preferably outwardly offset with reference to the major portion of the handle 19 as clearly shown in Figure 2, and the free end of the handle is provided with a hand grip portion 24.

The bar or link C, the main body portion of which is of rectangular cross-section, has one end thereof laterally enlarged to provide a head 25. The bar C bears on the outer surface of the door 10 and is slidably guided for movement longitudinally of the latter by means of the guide bracket E, the bracket E being secured to the door preferably by bolts. The head 25 is adapted to work between the arms of the forked head 18 and is provided with a slot 27 extending at right angles to the plane of the door adapted to receive the pin 23 of the lever G.

for sliding and pivotal movement. As will be evident, when the lever G is oscillated in a horizontal plane, the pin 23 will be swung about the pivotal axis of the lever on the brackets F, and through its connection with the bar C cause the same to slide relatively to the door. The end of the bar C remote from the head 25 is cut away on its outer side as clearly shown in Figure 2, thereby providing a tongue 28 and a vertically disposed shoulder 29.

The latch member D is pivotally connected to the tongue 28 by any suitable means such as rivet 30. As clearly shown in Figure 4, the latch member D is in the form of a flat plate cut away on the inner side adjacent the outer end to provide a raised hook member 31 presenting a downwardly and rearwardly inclined outer end face 32. Rearwardly of the face 32, the raised portion provides a vertical shoulder 33 and a downwardly and rearwardly inclined face 34. At the opposite end, the inner side of the plate is also cut away to receive the tongue 28. A ledge 26 is left along the lower edge of the plate adapted to abut the lower edge of the bar C to limit the downward movement of the latch plate D, the upper corner of the pivoted end of the plate being rounded off as clearly shown in Figure 4 so as to permit the same to swing upwardly. On its outer side adjacent the hook end thereof, the latch plate D is provided with a laterally projecting locking lug 35 adapted to engage within an opening 36 formed in the handle 19, when the latter is disposed in the full line position shown in Figures 1 and 2. It will be evident that the lug 35, when engaged within the opening 36 of the handle 19 serves to securely interlock the parts, preventing the latch D from being raised independently of the handle.

The stop bracket A is in the form of a flat plate applied to the door stop 11, the same having spaced lateral flanges 37 extending along the front and rear faces of the door stop 11, and fixed to said stop by screws or any other suitable means. The bracket A is also secured by two bolts 38—38 extending through the post and the upper and lower ends of the bracket, respectively. Adjacent the lower end, the bracket is provided with an outwardly projecting horizontally disposed shelf 39 provided with an upstanding flange 40 at its outer edge and a longitudinally extending rib 41 disposed parallel to the flange and spaced inwardly therefrom, and connected thereto by a transverse rib 141. The plate is also provided adjacent the top and bottom thereof with reinforcing ribs 42—42 connected by a vertically disposed web 43. Adjacent the shelf 39, the vertical plate portion of the bracket A is provided with a projection 44 presenting a vertically disposed shoulder 45 and an

inclined face 46 adapted to coact respectively with the shoulder 33 and the inclined face 32 of the latch D. As clearly shown in Figure 3, the rib 41 serves as a guide for the latch D and as a support for the handle 19 of the lever, when in the full line position. At the upper edge, the bracket A is formed with a horizontally disposed, outwardly projecting, hollow boss 47, having a solid, cylindrical end 48 of reduced size 75 forming a bearing for the locking plate B.

The locking plate B has a journal portion 49 at its upper end provided with an opening adapted to receive the bearing member 48 whereby the plate is pivotally mounted to swing in a vertical plane. The plate is retained in position by a washer interposed between the head of the upper securing bolt 38 and the projection 48 of the boss 47. The plate B is of such a length as to project behind the flange 40 of the shelf 39 when in its depending position. Along its front edge, the plate B is formed with a vertically disposed flange 50 adapted to abut a laterally projecting lug 51 formed on the handle 19. The lug and the flange are brought into abutting relation when the handle 19 is disposed in horizontal position resting on the rib 41, and the plate B is swung to its lowermost position. The flange and lug are provided with aligned perforations adapted to receive a padlock or the usual seal employed with devices of this character.

Assuming that the parts are in the position shown in the full lines in the drawing, when it is desired to open the door, the following sequence of operations takes place. The lead seal or other locking means is first removed, after which the plate B is swung to the dotted line position shown in Figure 1. The lever G is then swung in a horizontal plane on its trunnions by means of the handle 19, thereby disengaging the lug 35 on the latch plate D from the opening in the handle and causing the pin 23 through its slotted connection with the bar C to move the latter to the left as seen in Figures 1 and 2. The sliding movement of the bar C will cause the door to be positively forced away from the door stop since the end of the latch plate D is brought into abutment with the vertical web 43 of the stop bracket A. When the door has been thus partly opened, the hook portion of the latch D is disengaged from the projection 44 of the bracket A and the door fully opened by merely pushing the same in the usual manner. The latch may then be swung upwardly to dispose the same inwardly of the edge of the door so as to offer no obstruction. Upon the operator releasing his grip from the handle 19, the latter will drop downwardly automatically under the influence of gravity. It will be noted that the handle is thus disposed in a vertical posi-

tion inwardly of the edge 13 of the door, so that the same will offer no obstruction. The lever may be swung through an arc of 180° in performing the door opening operation to the position shown in dotted lines in Figure 2. When it is desired to close the door, the latter is moved to a position as near the stop 12 as can be conveniently done by the operator without the use of tools. 10 The handle G is then brought to the dotted line position shown in Figure 2, thereby projecting the bar C outwardly, the latch member D being first swung downwardly to a horizontal position. The hooked portion 15 of the latch D is then engaged with the projection 44 of the bracket A by pushing the door toward the stop, the inclined face 32 of the latch plate D engaging the inclined face 46 of the projection 44 swinging the latch upwardly on its pivot until the shouklder 33 thereof passes beyond the shoulder 45 of the projection 44, whereupon the latch will drop to the position shown in dotted lines in Figure 1 with the shoulders 20 45 and 33 in engagement. Thereupon the operator swings the handle G horizontally from the dotted line to the full line position shown in Figure 2, thus positively pulling the door to fully closed position. When 25 this condition has been reached, the handle 19 of the operating lever rests upon the rib 41 of the shelf 39 and the lug 35 of the latch plate D is engaged within the recess 36 to lock the latch plate to the handle. During 30 the operation of closing the door, the pivoted connection between the arm C and latch plate D will be retired within the guide E, preventing relative movement of the parts, the guide E acting as an additional means 35 for preventing lifting of the latch plate. The locking plate B is then dropped into position in front of the handle 19 with the lower edge of the plate disposed in back of the flange 40 and the flange 50 in abutment 40 with the lug 51. The padlock or seal may be then passed through the alined openings in the flange and lug. Although I have herein shown and described the latch plate D as held against upward movement both 45 by engagement of the lug 35 with the recess 36 of the handle and by the pivoted connection between the arm C and the latch plate D being retired within the guide E, it will be evident that either of these means alone 50 will serve the purpose and that the other may be entirely omitted.

Although I have herein shown and described the bracket A and the latch plate B as secured to the door post and the lever mechanism with associated parts as secured to the door, it will be evident that the position of the parts may be reversed without departing from the spirit of the invention.

I have herein shown and described what 60 I now consider the preferred manner of

carrying out my invention, but the same is merely illustrative, and I contemplate all changes and modifications that come within the scope of the claims appended hereto.

I claim:

1. In an operating and locking mechanism for a sliding door, the combination with a slidable, pulling member; of an abutment adapted to coact with said member to effect movement of the door when said member is operated; a lever for operating said member; a swingable latch plate mounted on said abutment and adapted to engage over said lever when the door is in closed position; and co-operating means on said plate and lever whereby the same may be interlocked.

2. In an operating and locking mechanism for a sliding door, the combination with a movable pulling member having a shoulder thereon; of an abutment means having a pair of shoulders thereon adapted to be engaged respectively by the end of the pulling member and the shoulder thereof to effect movement of the door during operation of said member; a lever for operating said member, said lever being arranged to move at an angle to the plane of said door and a latch plate movably mounted on said abutment means and adapted to engage over said lever when the door is in closed position to prevent movement of the lever in a door operating direction.

3. In an operating mechanism for a sliding door, the combination with a slidable pulling member; of an abutment adapted to co-act with said member; an operating lever pivotally mounted to swing in a plane at right angles to the door; and means on said lever engaging said member to effect movement thereof.

4. In an operating mechanism for a sliding door, the combination with a movable pulling member; of an abutment adapted to coact with said member; a lever pivotally mounted to swing in a plane at right angles to the door; an operating handle hinged to said lever to swing in a plane at right angles to said lever and assume a depending position under the influence of gravity; and means on said lever engaging said member to effect movement of the same.

5. In an operating mechanism for a sliding door member associated with a frame member, the combination with a pulling element slidably mounted on one of said members; of an operating lever element pivoted on said last named member to swing toward and from the same, said elements having inter-engaging operating means thereon comprising a slotted head on one of said elements and a pin on the other engaging within said slot; and an abutment means mounted on the other member adapted to co-act with said pulling element to effect

movement of the door upon said element being operated.

6. In an operating and locking mechanism for a sliding door member associated with a frame member, the combination with a bracket mounted on one of said members, said bracket being provided with a shelf; of a pulling element mounted on the other member; an operating lever pivotally mounted between its end portions on said last named member and operatively connected with said element, said lever being adapted to be swung into position to rest on said shelf when the door is closed; and a latch plate on said bracket adapted to be disposed in front of the lever, to retain the lever on said shelf and thereby lock the door in closed position.

7. In an operating and locking mechanism for a sliding door member associated with a door frame member, the combination with a bracket mounted on one of said members, said bracket being provided with a shelf having a flange thereon; a pulling element mounted on the other member; an operating lever pivotally mounted directly on said last named member and operatively connected with said element, said lever being adapted to be swung into position to rest on said shelf when the door is closed, said lever and element having means thereon adapted to inter-engage when the lever is on said shelf; and a latch plate on said bracket adapted to be disposed in front of the lever and engage behind said flange to retain the lever on said shelf and thereby lock the door in closed position.

8. In an operating and locking mechanism for a sliding door member associated with a frame member, the combination with a bracket mounted on one of said members, said bracket being provided with a shelf; of a pulling element mounted on the other member; an operating lever having its body portion pivotally mounted on said last named member and operatively connected with said element, said lever being adapted to be swung into position to rest on said shelf when the door is closed; and a latch plate on said bracket adapted to be disposed in front of the lever, to retain the lever on said shelf and thereby lock the door in closed position, said latch plate and lever having co-acting seal retaining means thereon.

9. In an operating and locking mechanism for a sliding door member associated with a frame member, the combination with a bracket mounted on one of said members, said bracket having abutment means thereon; of a supporting element on said bracket; a pulling bar slidably mounted on the other member; a lever mounted on said last named

member for swinging movement in a horizontal plane; a handle member hinged to said lever to swing in a vertical plane; inter-engaging means on said lever and bar to effect reciprocation of the latter upon oscillation of said lever; a pivoted latch plate on said bar adapted to coact with said abutment means to prevent movement of said bar relatively to said bracket; and means for locking said lever in fixed position on said bracket when the door is in closed position.

10. In an operating and locking mechanism for a sliding door member associated with a door frame member, the combination with a support fixed to one of said members; of a pulling element slidably mounted on the other member and adapted to be detachably connected to said support; a pivoted lever for operating said pulling element to either open or close the door, said lever being swingable to a position on said support to be supported thereby when the door is in closed position; and means for locking the lever and element to said support, said means including interengaging holding means on said lever and element.

11. In an operating and locking mechanism for a sliding door member associated with a door frame member, the combination with a support fixed to one of said members; of a pulling element slidably mounted on the other member; a pivoted lever for operating said pulling element, said lever being arranged for movement at an angle to the plane of said door member and adapted to swing into position on said support to be supported thereby when the door is in closed position; and means for locking said lever and pulling element to said support.

12. In an operating and locking mechanism for a sliding door member associated with a door frame member, the combination with a support fixed to one of said members; a pulling element slidably mounted on the other member, said element including a pivoted latch adapted to be detachably connected to said support; a guide within which the pivot end of the latch may be retired, said guide coacting with the latch to prevent disengagement of the same from the support; a pivoted lever for operating said pulling element to either open or close the door, said lever being swung to a position on the support to be retained thereby when the door is in closed position; and means for locking the lever and element to said support.

In witness that I claim the foregoing I have hereunto subscribed my name this 27th day of December, 1923.

STACY B. HASELTINE.
